UNITED STATES PATENT OFFICE.

RICHARD N. GARDNER, OF SAN FRANCISCO, CALIFORNIA.

TIME CALCULATOR.

Application filed January 15, 1924. Serial No. 688,407.

To all whom it may concern:

Be it known that I, RICHARD N. GARDNER, a citizen of the United States, residing at city and county of San Francisco, and State 5 of California, have invented certain new and useful Improvements in Time Calculators, of which the following is a specification.

My invention relates to the class of slide-rule calculators, and is particularly adapted 10 for calculating elapsed time.

The principal object of my invention is to provide a convenient device for calculating railway train schedules. Such schedules may extend over a continuous period of several days, and in order to make the usual 15 slide-rule calculators cover such a period, they must either be made unduly long, or the graduations must be so close together as to prevent accurate reading to the necessary time intervals. A calculator embodying 20 my present invention, however, may be made to cover the necessary period of several days, with sufficiently spaced graduations, and yet be of convenient and practicable length.

My present invention constitutes an improvement on the time calculator for which Letters Patent No. 1,458,649 were granted to me under date of June 12, 1923, in that, 25 in addition to the use set forth above, it may also be employed for calculating the elapsed time and over-time of workmen. For this reason it is of particular advantage in railway offices, in that the same device 30 may be used for calculating train schedules, over any ordinary period of time; for calculating the elapsed time, for pay-roll purposes, of train men; for determining the hours at which train men may be called for 35 or relieved from duty; and for calculating the over-time of train men in figuring pay-rolls.

It is to be understood, however, that my 40 device is not limited to the uses described above, but may be employed for determining the time and over-time of employees in any industry, or for calculating the elapsed time between any two known limits for any purpose whatsoever. Moreover, although my 45 invention is herein described and illustrated in its preferred form, it is to be understood that changes may be made in the form and construction of the device within the scope of the claim hereto appended.

50 My invention will now be fully described with reference to the accompanying draw-

ing, wherein the figure is a plan or face view, broken, of my time calculator.

In the drawing, the reference numeral 1 designates a body, in which is mounted, in any well known manner, a longitudinally movable slide 2. A marker 3, extending transversely across the body 1, is also longitudinally movable thereon, being mounted for such movement in any convenient and well known manner not shown in the drawings.

The body 1 is provided with a scale 4 indicating time as expressed by the clock, and extending for twenty-four hours, from 50 midnight to midnight. Thus the first half of said scale 4, from its left hand end to the center, is A. M. and the second, or right hand end is P. M. If desired, the figures of the first half of said scale can be printed 55 in light-face type, and those of the second half in dark face type, to differentiate between A. M. and P. M. In the particular rule shown in the drawing, the unit value of the clock scale 4 is ten minutes, but this 60 may be varied to suit the requirements of the use for which the device is intended. It is preferable to have the scale 4 equidistant from the ends of the body, but such 65 positioning is not essential. Likewise, the 70 total length of the body 1 may be varied to suit convenience, but I prefer to make it twice the length of the clock scale 4, for the reason that it then coincides with the 75 length of the slide 2, which must be twice 80 the length of said clock scale 4. The total 85 length of the particular rule shown in the drawing would therefore be twenty-four 90 inches, each hour on the clock scale 4 being 95 measured by one-half of an inch.

The slide 2 is provided with a plurality of elapsed time scales, there being five such scales shown in the drawings, and designated by the reference numerals 5, 6, 7, 8 and 9 respectively. These elapsed time 100 scales are positioned one below the other, as shown, and the spacing, as well as the unit value, of their graduations are the same as those of the clock scale 4, each mark representing ten minutes. For convenience in 105 reading, I prefer to arrange the figures of each elapsed time scale one above the other, the two lower figures representing minutes and those above representing hours, and 110 said figures are placed to the left of the line to which they refer. Thus for example, the figures appearing in the scale 9 im-

mediately to the right of the marker 3 should be read as "one hundred eight hours and twenty minutes", and such figures refer to the line immediately to their right. It is to be understood that each line of the elapsed time scales is marked by the figures representing its value, but for the sake of simplifying the drawing, I have shown only enough of such figures to illustrate the operation of the device.

10 The uppermost elapsed time scale 5, nearest the clock scale 4, begins with zero at a suitable zero-mark 10 at the longitudinal center of the slide 2, and extends continuously to twenty four hours at the right hand end of said slide. The next lower scale 6 begins with zero at the left hand end of the slide and runs continuously to 48 hours at its right hand end. The succeeding scales 7, 8 and 9 also extend the full length of the slide, beginning at the left, respectively, with 24 hours, 48 hours, and 72 hours, and ending respectively with 72 hours, 96 hours, and 120 hours. It will be seen, therefore, 25 that the value of any given mark on any one of the scales 6, 7, 8, or 9, is twenty four hours greater than the value of the corresponding mark on the scale immediately above.

30 This arrangement of the scales 5, 6, 7, 8 and 9 enables the calculation of elapsed time over a period of as much as five days, without necessitating the use of a rule of impracticable length, or one with unduly close 35 graduations. For example, to find the time elapsing between 10:30 A. M. and 8:30 P. M., slide 2 is set so that the zero-mark 10 coincides with the 10:30 A. M. mark on the clock scale 4, and the marker 3 is then set so that 40 its left hand edge coincides with the 8:30 P. M. mark on said scale 4, as shown in the drawing. The figures wanted, 10 hours, will then appear in the scale 5 immediately to the left of the marker 3. If the elapsed time is 45 wanted from 10:30 A. M. of one day to 8:30 P. M. of the following, or second day, the same settings of the slide 2 and marker 3 give the result, 34 hours, in the scale 6; and if the period extends to the same hour on the 50 third, fourth, or fifth day, the result will be found, with the same setting, in the scales 7, 8 or 9 respectively. It is to be noted that the effect of the scales 6, 7, 8 and 9 is to add the total value of the fixed clock scale 4, or 55 twenty-four hours, to whatever result is obtained from the first elapsed time scale 5. The scales 4, 5, 6, 7, 8 and 9 may be appropriately designated on the marker 3, as shown, by the legends Clock, 1st Day, 2nd 60 Day, etc.

At the lower edge of the slide 2 is a scale 11, which may be designated by the words Inflated Time upon the marker 3. Said scale 11 is used in figuring the over-time 65 of employees, for pay-roll or other pur-

poses, and is so designed as to give an apparent value for the over-time, which value can be added directly to the elapsed time and the sum multiplied by the straight time wage rate to give the total wage due the 70 employee. In the particular device illustrated, the inflated or over-time scale 11 is designed for employees receiving "time and one-half", or a 50% increase, for time over eight hours. If a different percentage 75 of increase for over-time is paid, or if the inflated rate begins after a different period, the scale 11 must be given a value different from that shown, as will be later explained, but the principle of the valuation of said 80 scale 11 is the same in all cases. When the same calculator is to be used for figuring pay-rolls of different classes of employees receiving over-time pay under different conditions, a number of slides 2 may be provided, identical in all respects except in the valuation of the scales 11. It would then be necessary only to change from one slide to another when changing from one class of 85 employees to another.

90 The graduations on the over-time scale 11 are spaced to correspond with those of the other scales in all cases. The unit value of the scale 11, however, is related to the unit value of the other scales as the excess 95 wage rate for over-time is related to the straight time or basic wage rate. Thus in the specific instance shown, the unit value of the scale 11 is 50% of that of the other 100 scales, or five minutes, and this valuation is adapted for use only in cases where the over-time wage rate is 50% greater than the straight time rate. If the over-time rate is "double-time", or an excess over the straight time rate of 100%, then the unit 105 value of the scale 11 must be 100% of that of the other scales, or ten minutes.

110 The inflated time scale 11 begins in line with the eight hour mark on the first elapsed time scale 5, as shown, only if the over-time wage is to be paid after eight hours of work. If overtime is to be paid after nine hours of work, then the scale 11 would begin in line with the nine hour mark 115 on said scale 5, and for other conditions accordingly. For convenience, when using the device for calculating from P. M. to A. M. instead of from A. M. to P. M. as shown, I provide a second portion 11' of the scale 11, bearing the same relation to the second day scale 6 as said scale 11 bears to the first day scale 5.

120 As an example of the use of the inflated time scale 11, the illustrated settings of the slide 2 and marker 3 may be used to calculate the wage due an employee who works from 10:30 A. M. to 8:30 P. M. The elapsed time, as given by the scale 5, is ten hours. The apparent over-time, as given by the scale 11, is one hour, which must be 125 130

added to the elapsed time and the sum multiplied by the straight time rate to arrive at the total amount due. Obviously, the result is the same as that arrived at by multiplying eight hours by the straight time rate, then multiplying the difference between ten and eight, or two hours, by the over-time rate, and adding the two results together, but the method involving the use of my apparatus 10 has the advantage of necessitating only one multiplication, at the straight time rate. It is to be noted moreover, that, by the use of my device, the straight time and over-time can be kept 15 separate, as is common practise in railway statistics.

Apart from the specific use of my calculator as described above, it will be seen that the function of the first elapsed time scale 20 5 is to indicate the arithmetical difference between any two given points on the fixed scale 4, and that the function of each of the other elapsed time scales 6, 7, 8, and 9 is to add a pre-determined quantity, or more 25 specifically the total value of the fixed scale 4, to whatever result is obtained from the elapsed time scale immediately above. The function of the inflated time scale 11 is to indicate, in terms of a pre-determined coefficient (in the specific instance shown, 50%) 30 the difference between a fixed point and any other point on the elapsed time scale 5.

This latter function is similar to that described in my said previous Patent No. 1,458,649, the improvement residing in making the scale 11 as an integral part of the slide 2, thereby simplifying the construction of the device by reducing the number of movable parts. 35

I claim:

A time calculator comprising a body member having a fixed scale representing a period of time and divided into units of equal value; and a slide having a plurality of scales of the same unit value as that of 40 said fixed scale, the first of said movable scales beginning with zero at the longitudinal center of said slide and extending to one end thereof and having a total value equal to that of said fixed scale, and each 45 of the succeeding movable scales beginning at the opposite end of said slide with a value equal to that of the preceding scale at the center of said slide and extending the full length thereof, and said slide having 50 two further scales each beginning with zero at points bearing a predetermined relation respectively to the first and second movable scales and advancing by units whose value bears a predetermined relation to the unit 55 value of the first mentioned movable scales. 60

In testimony whereof I have signed my name to this specification.

RICHARD N. GARDNER.
